United States Patent Office

Des. 176,286
Patented Dec. 6, 1955

176,286

AUTOMOBILE

Arthur Ross, Detroit, and Robert J. Scheelk, Oak Park, Mich., assignors to General Motors Corporation, Detroit, Mich., a corporation of Delaware

Application October 20, 1954, Serial No. 32,734

Term of patent 7 years

(Cl. D14—3)

Fig. 1 is a side elevation of an automobile incorporating our new design;

Fig. 2 is a top plan view of the automobile of Fig. 1; Fig. 3 is a front view of the automobile of Fig. 1; and Fig. 4 is a rear view of the automobile of Fig. 1.

The dominant features of our design reside in the full line portion of the drawings.

We claim:

The ornamental design for an automobile, substantially as shown and described.
